[57] **CLAIM**

The ornamental design for a gauge carriage support, guideway and drive housing for machine tools, as shown and described.

DESCRIPTION

FIG. 1 is a top plan view of a gauge carriage support, guideway and drive housing for machine tools showing my new design.

FIG. 2 is a bottom view but is not considered a part of the claimed design.

FIG. 3 is a side view.

FIG. 4 is a view of the opposite side.

FIG. 5 is a front view.

FIG. 6 is a rear view.
